Fisher, Mose & Moore

ATTORNEY

UNITED STATES PATENT OFFICE

JACOB KRONHEIM, OF CLEVELAND, OHIO

RESILIENT SEAT OR BOTTOM FOR CHAIRS, COUCHES, ETC.

Application filed February 18, 1931. Serial No. 516,593.

My invention relates to an improvement in resilient seats and bottoms for chairs, couches and the like, and in general my object is to provide simple and effective means and devices for attaching and suspending a flexible bottom by means of a set of coiled springs yieldably within a suitable frame, such as a rigid chair or couch frame.

In carrying out my general object, I employ brackets, clips or hangers which enable the bottom member to be attached to a rigid frame in a facile way and under a fixed tension but with freedom to move vertically within limits when suspended from said frame or brackets by coiled springs arranged perpendicularly and closely at the inner sides of the frame. The brackets or hangers may also be constructed and arranged to serve the double purpose of suspending the bottom member therefrom and of confining the coiled springs therein as will hereinafter be explained.

In the accompanying drawings, Fig. 1 is a plan view of a chair or couch frame embodying a flexible bottom and my improvement, and Fig. 2 is a sectional view vertically of the same structure, the compression or upholstery springs being omitted over a part of the flexible bottom. Fig. 3 is a perspective view of a corner portion of a frame and flexible bottom, including a modified form of bracket and suspensory support therefor, and Figs. 4 and 5 are horizontal and vertical sections of the same. Fig. 6 is a perspective view of a further modified form of attachment bracket.

Now, referring to Figs. 1 and 2, the invention as shown therein comprises an open rectangular frame A made of wood or other material, within which a flexible or pliable bottom or base member B made of woven textile material or materials such as canvas or burlap is tightly stretched. The dimensions of bottom piece B correspond closely to the inner dimensions of frame A to practically fill and close the rectangular opening, being attached at its seamed border edges to a series of angular brackets or hangers C which are nailed or screwed at spaced intervals to the inner sides of frame A. The

hemmed or seamed border portions of bottom member B contain a re-enforcing wire 2 which connects with the hangers or brackets C, the goods being pierced by the hanger or cut away in part to receive the hanger, and the wire being free to slide vertically in engagement with the main body or vertical keeper portion 3 of the hanger where spaced apart from frame A. As shown in Figs. 1 and 2, each hanger C is made of a flat strip of metal which is bent at right angles at one end to provide a lower arm 4 having a perforated extremity adapted to be nailed to the bottom edge of frame A, and the upper end of the vertical keeper portion 3 of this hanger is also bent at right angles and thence upwardly to provide a shorter angular extremity 5 which is perforated to permit it to be nailed against the inner side or vertical flat face of frame A.

The wired edge of bottom member B is adapted to move or slide vertically within the keeper portion of each bracket or hanger C, but normally bottom member B is maintained in a raised position therein by a set of coiled suspension springs D which hang downwardly or are suspended from hooks, staples or loops 6 affixed to or projecting inwardly from the side rails of frame A, see Fig. 1. Each spring D or a multiple number of them will support a load yieldingly and locally in the region of the spring or a series of springs but the lateral pull or strain on the fabric bottom member B is mainly carried or borne by the brackets C, said bottom flexing in some degree however in its body portion under the load and the load being also resiliently supported by the compression springs E banked or grouped upon bottom member B. According to old and established upholstering practices a covering of flexible material, padded upholstering or a cushion F is placed over the tops of springs E, and these springs partially compressed or placed under tension by fastening or tieing them or the covering to frame A. Thus the seating springs E and the suspension springs D coact to keep the covering or upholstering under tension and in shapely condition, and both sets of springs co-operate also in pro-

viding the desired soft resiliency for seating purposes, and ease and comfort being furthered still more by some additional yield in the fabric bottom member B itself.

Now referring to Figs. 3 to 6, sheet 2 of the drawings, a somewhat simpler and more compact form of the invention is shown therein, comprising supporting or suspensory brackets C', having perforated right-angled arms 7-7' adapted to be nailed or screwed to the upper and lower edges of the rails of frame A, the main body or keeper portion 8 of each bracket being relatively long or of the same height as the rail and spaced sufficiently apart therefrom to permit the suspensory springs D to be confined or housed between the rail and the vertical keeper portion 8 of the bracket. Openings 9 in upper arm 7 permit spring D to be hooked thereto and suspended therefrom, and the lower hooked end 10 of the spring is connected to the border wire 2 of bottom member A, which wire passes through the keeper space of bracket C' to hold this flexible bottom member stretched and under tension but also free to move vertically within the keeper or bracket under control of suspension springs D. In this form of suspension device the suspension springs D are supported directly by the brackets which hold the flexible bottom member B under tension, and each spring is always housed or covered by the bracket to prevent obstruction or interference with the expanding and contracting movements of its coils. Bottom member B and the brackets and suspension springs may also all be conveniently assembled as a unit and quickly and readily affixed within frame A with a minimum of labor and expense.

In Fig. 6, I show a bracket C'' corresponding to the bracket shown in Figs. 3 to 5, but having a reinforcing rib or channeled offset 11 in its vertical keeper portion 12. Further modifications might be made therein either to strengthen the same or to facilitate the hanging or movement of suspension spring D and border wire 2 therein.

What I claim, is:

1. A resilient seat or bottom for chairs, couches, etc., comprising a main frame, a flexible bottom member within said frame spaced from the inner walls thereof, a rigid border surrounding said bottom member, coiled springs suspended from said frame and connected with said rigid border of said bottom member, and means for maintaining said flexible bottom member under tension and stretched and axially aligned with respect to said frame independently of said springs.

2. A resilient seat or bottom for chairs, couches, etc., comprising a main frame, coiled springs suspended vertically from said frame, a flexible bottom member within

said frame spaced from the inner walls thereof and supported for vertical movement within said frame by said springs, and tension-applying means for all sides of said bottom member connected to said frame. 70

3. A resilient seat or bottom for chairs, couches, etc., comprising a main frame, a flexible bottom member and suspension springs therefor connected with said frame, and hanger means fixed to said frame and slidably interengaged with all sides of said bottom member for guiding and stretching said flexible bottom member within said frame.

4. A resilient seat or bottom for chairs, couches, etc., comprising a main frame, a flexible bottom member having a stiffening border wire, suspension springs connecting said border wire with said frame, and metal keepers attached to said frame for confining said border wire movably in respect to said frame. 80

5. A resilient seat or bottom for chairs, couches, etc., comprising a frame having angular hangers affixed thereto, a wired bottom member made of flexible material slidably connected with said hangers, and suspension springs for supporting said bottom member yieldingly within said frame. 90

6. A resilient seat or bottom for chairs, couches, etc., comprising an open frame having angular brackets affixed to all its inner sides, springs supported by said brackets, and a flexible bottom within said frame spaced from the inner walls thereof, connected with said springs and slidably interengaged with said brackets. 100

7. A resilient seat or bottom for chairs, couches, etc., comprising an open frame, brackets secured to all inner sides of said frame, springs suspended from said brackets, and a flexible bottom having a reinforced portion connected with said springs and slidably interengaged with said brackets. 105

8. A resilient seat or bottom for chairs, couches, etc., comprising a frame, metal brackets at the inner sides of said frame, a flexible bottom made of woven fabric having a border seam containing a reinforcing wire slidably connected with said brackets, 115 and suspension springs for said bottom supported by said brackets.

9. A resilient seat or bottom for chairs, couches, etc., comprising a frame having angular brackets affixed thereto, a flexible sheet 120 attached at its edges to said brackets and held under tension thereby within said frame, suspension springs supporting said sheet for vertical movement in respect to said frame and brackets, and cushioning 125 springs seated upon said flexible sheet.

10. A resilient seat or bottom for chairs, couches, etc., comprising a frame having rails, angular brackets affixed to the inner sides of said rails, suspension springs con- 130

fined within said brackets, and cushioning springs having a supporting member yoked to said brackets and supported for vertical movement within said frame by said suspension springs.

5 In testimony whereof I affix my signature.

JACOB KRONHEIM.
